UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

LOOM-SHUTTLE.

1,091,868.

Specification of Letters Patent. Patented Mar. 31, 1914.

Application filed September 12, 1912. Serial No. 719,957.

To all whom it may concern:

Be it known that I, EDWARD S. STIMPSON, of Hopedale, in the county of Worcester and State of Massachusetts, have invented an 5 Improvement in Loom-Shuttles, of which the following is a specification.

The present improvement consists in the means for mounting a porcelain snubbing post in an automatically threading loom 10 shuttle having a sheet metal threading device so that the yarn will run over said porcelain post on its way from the longitudinal thread passage of the shuttle to the eye thereof.

15 The present improvement is illustrated in the accompanying drawings, wherein—

Figure 1, is a plan view of the eye end of the shuttle, a portion being broken away to aid in the illustration. Fig. 2, is a similar view showing the improved portions in horizontal section. Fig. 3, is a side view of the shuttle looking toward the shuttle eye and parts being broken away and shown in vertical section. Fig. 4, is a transverse section in the plane indicated by the line 4—4 in Fig. 1. Fig. 5, is a perspective view of the sheet-metal threading device, parts being broken away, and of the porcelain snubbing post used therewith. Fig. 6, is a detail view of the holder for said porcelain snubbing post removed from the sheet-metal threading device.

As shown in the drawings, A, is the shuttle having a slotted side-eye B, in one side, 35 and C, is the sheet-metal threading device which is substantially like that shown in the United States Letters Patent of Stimpson, No. 933,497, and which has a longitudinal thread passage a, through which 40 the thread passes on its way from the weft-carrier within the shuttle to the eye B. The thread eye B, is guarded at front and back by means of hollow porcelain snubbing posts, D, and E, over which the thread runs 45 as the shuttle travels in its different flights. There is a third porcelain snubbing post F, at the juncture between the longitudinal thread passage a, and the eye B, over which the thread runs whichever way the shuttle travels. These snubbing posts are made of vitreous material, such as porcelain, which withstands the wear incident to the employment of worsted or similar rough yarns. These porcelain posts are hollow cylinders,

because the hollow form facilitates replacement when needed.

In the respects thus far described the shuttle is similar to that disclosed in Letters Patent of the United States of John F. O'Neill, No. 1,064,245, granted June 10, 1913.

The present improvement consists in the means employed for holding the porcelain post F, in position. For this purpose there is provided a sheet-metal holder G, which is a cylindrical sheet-metal tube, open at its bottom for the insertion of the post F. At its middle this holder is cut away as shown at b, so as to expose the post F, in the path of the thread. The holder has a slot d, at its upper end which fits over a depending flange e, of the sheet-metal threading device and which aids in positioning the holder and in retaining it in place. The holder is firmly secured to the sheet-metal threading device by means of solder f, along the contiguous surfaces.

The porcelain post F, fits snugly within the holder G, and, consequently, when the holder is fastened to the sheet-metal threading device and the porcelain post is in place, 80 all can be handled and assembled in the shuttle as a single part. When the threading device with the holder G, and post F, is placed within the shuttle the post F, is maintained securely in place since it cannot 85 move downwardly because its lower end is substantially flush with the lower end of the holder G, and hence just above the floor of the passage a, constituted by the wooden body of the shuttle; and it cannot move 90 upwardly because seating against the flange e, of the sheet-metal threading device.

The porcelain post F, can be readily replaced in case of need by simply removing the sheet-metal threading device from the 95 shuttle and taking out the old post and replacing it by a new one.

I claim—

1. An automatically threading loom shuttle having a detachable sheet-metal threading device with a longitudinal thread passage communicating at its forward end with the side-eye of the shuttle and having a depending flange; a hollow cylindrical metallic holder open at its lower end and slotted 100 at its upper end to straddle said flange and being further secured to the sheet metal threading device by solder along the meet- 105

ing surfaces; and a porcelain snubbing post fitting snugly in said holder and seating at its upper end against said flange, the holder being open at its middle to expose the porcelain snubbing post to the path of the thread.

2. An automatically threading loom shuttle having a detachable sheet-metal threading device with a longitudinal thread passage communicating at its forward end with the side-eye of the shuttle; a hollow cylindrical metallic holder open at its lower end and secured to the sheet-metal threading device; and a porcelain snubbing post fitting snugly in said holder, the holder being open at its middle to expose the porcelain snubbing post to the path of the thread.

3. An automatically threading loom shuttle having a detachable metal threading device with a longitudinal thread passage communicating at its forward end with the side-eye of the shuttle; a hollow cylindrical metallic holder open at its lower end and

secured to the metal threading device; and a porcelain snubbing post fitting snugly in said holder, the holder being open at its middle to expose the porcelain snubbing post to the path of the thread.

4. An automatically threading loom shuttle having a detachable metal threading device with a longitudinal thread passage communicating at its forward end with the side-eye of the shuttle; a metallic holder open at its lower end and carried by the metal threading device; and a porcelain snubbing post fitting in said holder through its lower open end, the holder being provided with an opening to expose the porcelain snubbing post to the path of the thread.

In witness whereof, I have hereunto signed my name in the presence of two subscribing witnesses.

EDWARD S. STIMPSON.
